FOWL BLEEDER

Willie M. Shoffner, Dayton, Ohio

Application December 21, 1950, Serial No. 13,521

Term of patent 14 years

(Cl. D12—2)

To all whom it may concern:

Be it known that I, Willie M. Shoffner, a citizen of the United States, residing at Dayton, in the county of Montgomery, State of Ohio, have invented a new, original, and ornamental Design for Fowl Bleeder, of which the following is a specification, reference being had to the accompanying drawings, forming a part thereof, wherein:

Figure 1 is a perspective view of a fowl bleeder, showing my new design.

Figure 2 is a side perspective view of the device.

Figure 3 is a fragmental perspective view showing the bottom of the device.

I claim:

The ornamental design for a fowl bleeder, substantially as shown.

WILLIE M. SHOFFNER.
